METHOD OF REMOVING SCRAP AND FOLDING AND GLUING CARTON BLANKS AND MACHINE THEREFOR

Samuel Bergstein, Cincinnati, Ohio

Application October 17, 1932, Serial No. 638,111

15 Claims. (Cl. 93—58)

My invention relates to methods of continuously removing scrap sections from cut and scored carton blanks, and for then folding and pasting the carton blanks while the blanks move continuously and in sequence, and to machines in which these several operations are performed.

The customary procedure in making knock-down cartons is to remove the scrap sections from the blank by hand before inserting the blanks in the folding and gluing machine. With this procedure difficulty is encountered, since the blanks will not feed freely because cut-out portions catch in the edges of cut-out portions of other cartons. Such method, therefore, requires unnecessary handling, increases the cost of production, and invariably results in a considerable loss by spoilage of cut-out blanks.

It is an object of my invention to provide a machine with which it is possible to remove the scrap materials from the cut-out sections, apply adhesive, fold, and effect adhesion, in one continuous operation.

Another object of my invention is to provide a machine in combination with a folding and gluing machine, which will permit the feeding of the blanks with the scrap sections remaining in them, and to then remove the scrap sections automatically just prior to and while moving the blank without interruption to the folding and gluing operation.

Another object of my invention is to provide a special type of folding mechanism in which a carton with ledge portions is automatically formed on a standard folding and gluing machine.

Specifically it is an object of my invention to provide a machine which will automatically remove the scrap sections of a carton blank while it is being fed to the folding and gluing operations which complete the forming of the knock-down carton. In the sequence of operations in the machine, three glue joints are formed, two to form legs, and another to complete the sealing of the carton in knocked-down tubular condition.

These and other objects will be more specifically pointed out in the specification and the drawings forming part of this application.

In the drawings:—

Figure 1 is a plan view of part of the machine.
50 Figure 1a is a fragmentary plan and the continuation of Figure 1.

Figure 2 is an elevation with part in section taken on the line 2—2 of Figure 1.

Figure 2a is an elevation in section taken on 55 the line 2a—2a of Figure 1a.

Figure 3 is a plan of a blank that can be folded and pasted on the machine.

Figure 4 is a perspective of the blank after removing the scrap sections and making the first fold.

Figure 5 is a perspective of the carbon after completing the folding and gluing operations.

Figure 6 is a perspective of the special type of foldover plate used on the machine.

Figure 7 is a section taken on the line 7—7 of 10 Figure 6.

Figures 8, 9, and 10 are sections taken on the respective lines indicated in Fig. 6.

Fig. 11 is a partial plan view of the final folding and pressing means.

Fig. 12 is a partial perspective view of the carton in set up condition.

For the purpose of illustrating my invention, I have shown in part the usual mechanism as used on folding and gluing machines. The machine is supported on the side frame castings 1 and 1a. Mounted on the side frame castings are bearing brackets 2 and 2a in which is rotatably mounted a driven shaft 3. Fixedly mounted on the shaft there is a feed roller 4 for the carton blanks 5. The blanks are stacked flatwise one on top of the other in a sloping hopper 6. Another feed roller 7 is fixed on another shaft 8 which is rotatably mounted in bearings provided in the brackets 2 and 2a.

Fixedly mounted on the shaft 8 are two pulleys 9 and 9a for driving endless belt conveyors 10 and 10a. These belts extend towards and are around other pulleys 11 which are fixed on another shaft 12. The shaft 12 is rotatably mounted in bearings provided in brackets 13 and 13a fixed on the side frame of the machine.

Above the conveyor belts just described are other hold-down belts 14 and 14a. These belts pass under a series of rollers 15 and 15a which are rotatably mounted on studs 16 fixed in plates 17 and 17a. These plates are rotatably mounted on a shaft 18, and fixed between them on the shaft are pulleys 19 and 19a. These pulleys provide the driving means for the hold-down belts. Other rollers 20 are provided on the tops of the belts to tension them. These belts just described apply pressure to the carton on the top and hold it down firmly on the conveyor belts so that the carton will be carried through the machine.

On each side of the machine are guide rails 21 and 21a to keep the cartons in their proper line of travel. Another guide or surface plate 23 is provided to keep the carton flat while the scrap is being removed. This plate has an opening 24.

extending through it, which permits a bent end 25 of a spring member to press the scrap section 25a through it in the manner shown at 26 in Figure 2.

- 5 The spring member has a straight shank 27 which extends through and is held fast in a shaft 28 by means of a set screw 29. The shaft 28 is rotatably mounted in bearings 30 provided at the sides of the machine. Other spring members 10 with bent ends 31 have straight shanks 31a which extend through the shaft 28. These spring members are also held in place on the shaft 28 by means of the set screws 31b. The bent portions of these last mentioned springs are so positioned 15 that they will press on the blank, and whenever a cut-out section comes under them, the cut-out section will be ejected from the hole.

Rigidly mounted on the standards are pedestals 32 having bosses with holes 32a therein. Mounted 20 and secured in the holes are two shafts 33 and 33a. These shafts adjustably support a motor base 34. Attached to the base is a motor 35 having an extending shaft 35a. Fixed on the motor shaft is a hub 36 with slots 36a. In these slots 25 are fixed radially extending blades 37, which are so positioned that they will slightly contact with a depressed scrap section 25a, as can be seen by referring to Figure 2. The blades are rotated rapidly by the motor, and whenever a scrap section 30 is depressed, the blades will remove the section from the blank while it moves uninterruptedly through the machine.

After the removal of the scrap section the blank 35 passes beneath gluing rolls 39 where glue is applied in stripes in the usual manner along the sections of the blank indicated at 40, 40a, and 40b. Rigidly mounted on the bed of the machine is a plate 41. Integral with the plate is a rail 42 with a top surface 42a over which the blanks slide. 40 A perpendicular wall 42b of this rail is flat at one end 42c over its entire height. The other end 43 of the rail is undercut to form an L-shape on the underside 43a. From this end 43, to a point 43b close to the other end, the L-shaped underside opening is gradually diminished until it intersects the perpendicular surface or wall 42b. Referring to Figure 6 and the various sections taken from this figure, it will be seen how the underside L-shaped section is developed.

45 A top surface pressure plate 44 shown in Figure 1a and in dotted lines 44a in Figure 6, has a narrow upturned end 45. It has a tapered side 45a which corresponds to the slope of the diminishing L-shaped underside of the rail. This plate is held rigidly in place by means of rods 46 or their equivalent. The tapered edge of this plate is positioned so that it will be just far enough away and admit a carton to pass between it and the slope of the underside L-shaped walls of the rails.

50 Rotatably mounted in bearings provided in the side frame is a shaft 47. On this shaft there are fixed pulleys 47a which drive conveyor belts 48 extending the full length of the machine. At 55 the top of the machine there is another rotatable shaft 49 having pulleys 49a for driving other conveyor belts 50. These other belts are in line with the lower conveyor belts and provide the means for holding the blanks in contact with the lower belts so that the blanks will be carried through the required sequence of operations. These other conveyor belts 50 are illustrated in Fig. 11.

55 Directly in front of the L-shaped rail are two pinch rolls 51 and 51a fixedly mounted on shafts 52 and 52a. These shafts are rotatably mounted

in bearings 53 which are rigidly mounted on the main frame of the machine. The pinch rolls squeeze down the section of the blank folded over by the L-shaped rail and insure that this section will be glued together. Beyond these pinch rolls 51 and 51a are the turn over plates 44a in conjunction with the belts 50, and beyond these are the lower long pinch roll 54 and the upper pinch rolls 54a, 54b, and 54c.

5 For purposes of explaining my method and machine, I have illustrated an egg carton blank 5 during its assembly, the blank being like that shown in my co-pending application Serial No. 635,970, filed October 3, 1932. Certain sections 10 25a of the blank are cut so that they can be completely removed. These sections are scrap and must be removed in this particular type of carton. Other sections 55 are also cut and must also be removed to form slots 56a.

15 The cutting out of the blank is performed in 20 multiple by any usual die press having cutting blades which form the cuts shown in Figure 3. The scrap which is defined by the cuts will not fall out of itself, but remains in the blank, thus keeping the blank flat and permitting automatic feeding 25 from a hopper. The fact that the scrap remains in place in the blank is the usual experience of the art.

20 The blanks, as illustrated in Figure 3, are 30 stacked on top of each other in the hopper, with their edges 57 adjacent the feed rollers. The feed rollers push them forward and the blanks, one at a time, pass underneath the spring members. The spring members push down on the sections 25a and depress them so that the whirling 35 blades will hit them and knock them from the blank. The other spring members push on the sections in the slots 55 and eject them from the blanks, leaving the slots clean. After removal of the scrap sections, the blanks pass between the 40 discs 39 and glue is applied to the sections 40, 40a, and 40b.

45 It will be noted that the blanks are now free from the scrap and glue applied to them individually, and they are being conveyed in rapid 45 succession to the folding mechanism.

50 It would be impractical to attempt to feed carton blanks having scrap removed which frees articulated flaps for slightly folding upwardly, by any usual mechanical feed at economical speed. In the past the art has had to resort to individual blank hand feeding.

55 It is thus very important to my invention that I have conceived of the improvement of establishing by automatic machinery a rapid succession of blanks, which blanks could not be so fed unless the adhering scrap which holds down the articulated flaps is removed in the movement of the blank toward the gluing and folding mechanisms.

60 One way of expressing my improvement in method is that as a way of providing a succession of cut blanks to a folding and gluing mechanism, I pass the blanks through any feeder available in the art, convey the blanks toward the gluer and folder by any available conveyor or series of conveyors available in the art, and during this feeding I remove the scrap by any available means, particularly when applicable to a moving blank.

65 The preferred mechanism for removing the 70 scrap is novel, but I could also employ a series of compressed air jets, a traveling punch, or any other mechanical device.

75 Thus, I have an invention which has method aspects, which I believe to be patentable as such.

The underside of section 40b will slide over the surface 44 and its top surface will slide underneath the hold-down plate 44. While the carton continues to pass through the machine, the section 40b will be folded over gradually along the score lines 58 and 58a until there is an overlapped or pleated fold as is illustrated at 59 in Figure 4. Section 60 will then form a longitudinal leg the full length of the box. After making the bend 10 and folding, the carton passes between the pinch rolls to insure the gluing together of the section 60.

After leaving the pinch rolls 51 and 51a the carton is conveyed forward through the turn over plates 44a, and it is bent over along the score line 61. When it is folded over on this line the glued flap 62 will be pasted to the cover surface 63 along the line 64. At the same time that this fold is being made, the section 40a will be pasted to the surface 65 adjacent the line 61, and all the adhesive surfaces will be pressed by the pinch rolls 54, 54a, 54b, and 54c. Folding and pasting the carton in this manner results in a collapsed carton 66 as illustrated in Figure 5, the section 20 40a providing the other longitudinal leg the full length of the carton, which has been fully described in my co-pending application, as hereinbefore referred to.

Having thus described my invention, what I 30 claim as new and desire to secure by Letters Patent, is:—

1. In combination with a machine for folding and gluing carton blanks having cut-out scrap portions which require removal, a conveyor for carrying individual blanks to said machine, and means effective during the interval when the blanks are carried on said conveyor for ejecting 35 said scrap portions.

2. In combination with a machine for folding and gluing carton blanks having cut-out scrap portions which require removal, conveying means for carrying individual blanks in said machine, and means effective during the interval when the blanks are carried by said conveying means for 40 partially ejecting said scrap portions by pressing said scrap portions outward, and means for completely ejecting the pressed out scrap portions.

3. A gluing and folding machine for forming knock-down carton blanks, comprising a conveyor 50 for carrying flat blanks, means for applying adhesive to predetermined bands on said blanks, means for forming pleated folds in each blank, whereby one supporting leg is formed while they are in motion, and means for folding over side walls of said blanks for forming an additional supporting leg for each carton, and means for securing 55 said blanks in flat tubular condition.

4. A gluing and folding machine for forming knock-down cartons comprising means for feeding 60 flat blanks, a conveying means for carrying the flat blanks, means for applying adhesive to predetermined bands on said blanks, means for forming pleated folds in each blank, whereby one supporting leg is formed while they are in motion, and means for folding over side walls of 65 said blanks for forming an additional supporting leg for each carton, and means for securing said blanks in flat tubular condition, all of said adhesive applying and folding operations being carried out while said blank is in continuous motion.

5. A method of forming knock-down containers having legs supporting the container base at the side edges, which consists in moving flat 70 blanks along, applying adhesive to each blank, forming a pleated fold in each blank where the

adhesive is applied, then folding over a side of each blank so that it overlies an unfolded portion of each blank so that following said pleating and folding operation each blank will assume collapsed tubular shape.

6. A method of forming knock-down containers having legs supporting the container base at the side edges, which consists in moving flat blanks along, applying adhesive to spaced portions of each blank, forming a pleated fold in each blank 10 where the adhesive is applied to one portion to form a leg at one side, then folding over a side of each blank at another portion where the adhesive is applied to form a leg at the other edge, and so that it overlies an unfolded portion of each 15 blank so that following said pleating and folding operation each blank will assume collapsed tubular shape.

7. In a machine of the character described, means for conveying blanks, means for applying 20 parallel stripes of adhesive to said blanks as they are conveyed, means for forming a pleat in each blank along one of the stripes of adhesive while the blank is being conveyed, means for folding a portion of said blank along another stripe of 25 adhesive to overlie the pleated fold to contact a portion of the blank with a third stripe of the adhesive between the contacting portions, and means to press the completely folded and pleated blank during further passage of the blank to 30 press the adhering portions together.

8. In a machine of the character described, means for conveying blanks having cut-out scrap portions requiring removal, means for ejecting 35 said scrap portions from the blanks while the blanks are being conveyed, means for applying parallel stripes of adhesive to said blanks as they are conveyed, means for forming a pleat in each blank along one of the stripes of adhesive while the blank is being conveyed, means for folding a 40 portion of said blank along another stripe of adhesive to lie across the pleated fold to contact a portion of the blank with a third stripe of the adhesive between the contacting portions, and means to press the completely folded and pleated 45 blank during further passage of the blank to press the adhering portions together.

9. In a machine of the character described, means for conveying blanks, means for pressing the scrap portions out from the blanks while they 50 are being conveyed, means for ejecting the pressed out scrap portions while the blanks are being conveyed, means for applying parallel stripes of adhesive to said blanks as they are conveyed, means for forming a pleat in each blank along 55 one of the stripes of adhesive while the blank is being conveyed, means for folding a portion of said blank along another stripe of adhesive to overlie the pleated fold to contact a portion of the blank with a third stripe of the adhesive 60 between the contacting portions, and means to press the completely folded and pleated blank during further passage of the blank to press the adhering portions together.

10. In a machine of the character described, 65 means for conveying a carton blank having cut-out scrap portions requiring removal therefrom, means for pressing an advanced end portion of the scrap out from the blank as it is conveyed along, and means moving in the direction opposite to that of conveyance of the blank engaging said pressed out end portion of the scrap and completing the removal of the scrap from the blank.

11. In a machine of the character described, 75

means for feeding blanks having cut-out scrap portions, means for carrying said blanks, means for removing the scrap portions as the blanks are carried, means for applying adhesive to portions of the blank as it is carried, means for folding the blank along the portions having the adhesive as the blank is carried, the folding at one portion forming a pleat, and the folding at another portion having adhesive forming the blank into a flat tubular knock-down container, and means for pressing said flat, tubular container at all of the folded and adhesive bearing portions during carrying of the container.

12. In a device for removing scrap portions from carton blanks, a support for the blanks, means for forcing the blanks individually along the support, means for feeding the blanks successively to the forcing means, said support being open downwardly where the scrap portions of the blanks pass along the support, means bearing down on the blanks only within the lateral limits of the scrap portions, effective to displace the scrap portions downwardly from the blanks, and means below the support, for completely removing said scrap portions from the blanks by engagement with displaced extensions of the scrap portions.

13. In a machine for folding carton blanks by moving the blanks along a defined path, two folding members, one above the other, along said path, the lower member having an upstanding element at one side of and along said path with a flange overhanging the path, beginning near the approach end of the member and gradually being thinner as it extends toward the leaving end thereof, forming a space thereunder which gradually increases in height, and the upper member lying above the top of said upstanding

element between its approach end and the beginning of said flange and being spaced inwardly from said upstanding element toward the middle of the path where it lies above said element, and being gradually widened in its extent toward the leaving end of the member and extending downwardly in said extent and, for a substantial distance having its edge lying within the space under the flange, whereby a blank, fed along the top of the upstanding element under the upper member, is gradually folded into a pleat around the edges of the upper member and the flange of the upstanding element.

14. In a device of the character described, means for moving a carton blank having a scrap portion lodged therein, and devices successively engaging the scrap portion at opposite surfaces of the blank in the course of the blank movement, to remove the scrap portion from the blank, both engaging devices being of open construction where they engage the scrap portion, leaving the scrap portion free to pass away from said engaging devices as soon as the respective devices have acted upon said portion.

15. In a device of the character described, means for moving a carton blank having a scrap portion lodged therein, means engaging the scrap portion at one surface of the blank to initiate removal of the scrap portion, and means engaging the partially removed scrap portion at the opposite surface of the blank, to complete the removal of the scrap portion, both of said engaging means being of open construction where they engage the scrap portion, leaving the scrap portion free to pass away from said engaging means as soon as the respective engaging means have acted upon said portion.

SAMUEL BERGSTEIN.
